[57] CLAIM

The design for a compact enclosure for personal computers, as shown and described.

DESCRIPTION

FIG. 1 is a top, front, left side perspective view of a compact enclosure for personal computers showing my new design.

FIG. 2 is a top plan view thereof;

FIG. 3 is a front elevational view thereof;

FIG. 4 is a bottom plan view thereof;

FIG. 5 is a right side elevational view thereof;

FIG. 6 is a back side elevational view thereof.

*Fig. 1**Fig. 2**Fig. 3**Fig. 5**Fig. 4**Fig. 6*
